UNITED STATES PATENT OFFICE.

AUGUSTUS U. PAGE AND JOHN BRAGG, OF CLEVELAND, OHIO.

OIL-BURNER.

SPECIFICATION forming part of Letters Patent No. 396,049, dated January 8, 1889.

Application filed May 2, 1887. Serial No. 236,872. (No model.)

To all whom it may concern:

Be it known that we, AUGUSTUS U. PAGE and JOHN BRAGG, of Cleveland, in the county of Cuyahoga and State of Ohio, citizens of the United States, and residents of said city, have invented certain new and useful Improvements in Oil-Burners; and we do hereby declare that the following is a full, clear, and exact description of said invention, such as will enable others, skilled in the art to which it pertains to make and use the same, reference being had to the annexed drawings.

Our invention relates to the class of oil-burners adapted to burn hydrocarbon oils under steam-boilers and in furnaces; and it consists in the arrangement of parts and the combination of the elements of combustion, as herein described, and specifically pointed out in the claims.

The object of the invention is to facilitate the use of crude petroleum-oil as a fuel by securing more perfect combustion with economy of material, to avoid the danger of leakage or dripping of unconsumed oil from the burner, which is a common fault with oil-burners of this class now in use, and to obtain a quieter and more equable flame.

In the drawings, Figure 1 is a central vertical sectional view of a burner embodying our invention. Fig. 2 is a plan view of the top of the front portion or nozzle. Fig. 3 is an elevation of the nozzle, showing the escape-vent. Fig. 4 is a detached sectional view showing a modified form of construction of the internal parts of the burner. Fig. 5 shows the preferred method of attaching the burner under a steam-boiler, the burner and boiler being shown in elevation, and the brick-setting in section. Fig. 6 is a partial sectional view on the line xz of Fig. 5, showing the preferred distribution of air-passages beneath the boiler. Fig. 7 is a detached view, in elevation, of the burner and its attachments when arranged under a boiler, as in Fig. 5, and Fig. 8 is a plan view of the burner and attachments shown in Fig. 7.

The burner consists, essentially, of a shell or ease, Λ , preferably of cast metal, gradually tapering at about one-third its length from the front end to a diameter of about half that of the main body of the shell, thus form-

ing a nozzle, a , which at its distal end is flattened horizontally and somewhat fan-shaped, so that the outlet is in the form of a long narrow slot, b ; and this opening, as seen in Fig. 3, is made somewhat narrower in the center than at the ends, and widens gradually and regularly from the center toward the ends, in order to prevent a too free escape directly in front of the internal steam-jet and insure an even distribution of the combustible mixture of oil, steam, and air throughout the entire length of the escape-vent b . The nozzle a may, if preferred, be formed separately from the ease Λ , and attached thereto by a screw-thread; but as there is no liability of the nozzle to burn away at the outlet and need replacing we prefer to cast the shell and nozzle in one piece. The rear end of the shell Λ is closed by a cap, B , screwed on.

C is a pipe entering the shell Λ near the rear end and passing forward centrally in the shell Λ to near the point where the converging walls of the shell merge into the nozzle a , where the pipe C terminates in a free open end.

D is a pipe surrounding the pipe C and of about twice its diameter, ending a short distance back of the end of pipe C . Another pipe, E , enters the shell Λ near the rear end, and terminates in a nozzle, e , parallel with the pipes C and D , but terminating some distance farther back in the shell. A smaller pipe, F , enters centrally along the pipe E and terminates in a reduced opening opposite and near to the inner end of the nozzle e . The pipe C is connected with the oil-supply. D and F are connected with a steam-superheater, and E , either immediately outside the shell or at any suitable distance, is freely open to the outer air. We prefer to take the air-supply from the space above the nozzle of the burner, or through a bend or coil carried through the fire-pit, thereby securing air already more or less heated. All the pipes are provided at any convenient point outside the shell with suitable valves.

The pipes C , D , E , and F may enter the shell Λ at the top or bottom, or on either side, as may be most convenient in any given location, or they may all enter the rear end of the shell through the cap B . The parts of C , D ,

and E contained wholly within the shell may be cast in one piece, as shown in Fig. 4.

In the operation of the device oil is admitted through the pipe C, and simultaneously 5 superheated steam is admitted through the pipes D and F, that entering through F having the greater velocity. The jet of steam from the contracted end of the pipe F, passing through the nozzle e, draws in air through 10 the pipe E, and the mingled steam and air pass forward around the pipe D to the nozzle A. The steam entering through D and passing around the pipe C heats the oil in C nearly 15 to the vaporizing-point, and takes up the oil as it escapes from pipe C in this condition, turning the oil into a spray and mingling at the same time with the mixed steam and air which fill the shell from the nozzle e, thus 20 forming a gaseous mixture permeated with the oil, which mixture of air, steam, and oil passes into the nozzle a, from which it emerges 25 through the vent b in the form of a broad thin diverging sheet of gaseous spray, which, when ignited, burns steadily and quietly, like 30 a lamp-flame, without the cutting blast effect of a flame discharged in a columnar or tubular shape, or from a circular opening, and much greater heating effect is obtained from the expenditure of an equal amount of oil. 35 The proportion of air introduced is regulated by the velocity of the steam introduced through the pipe F, the greater velocity drawing in more air, and it is desirable to have the proportion of air largely preponderate over that of the steam, for which reason the 40 steam-pipe F may be as small as one-quarter

inch internal diameter, and still further reduced at the end, while the air-inlet pipe E may have a diameter of one inch or more.

By using dry superheated steam, a much 40 larger proportion of air, a complete and perfect mixture of the air, steam, and oil—both being heated before the mixture takes place—we obtain more perfect combustion and a more intense heat than has been hitherto accomplished, while the diffusion of the flame secures more complete utilization of the heat produced. 45

What we claim as our invention, and desire to secure by Letters Patent, is— 50

1. In an oil-burner, the combination of the following elements, to wit: a shell or case having a contracted nozzle, with a centrally-compressed and laterally-expanded outlet, with an air-inlet pipe to said case having an 55 expanded chamber with contracted outlet, and inclosing within such chamber a steam-pipe, and an oil-inlet pipe to said case surrounded by a separate and independent steam-pipe, substantially as described. 60

2. An oil-burner composed of a shell having a contracted nozzle, with centrally-compressed and narrow laterally-elongate opening, and containing an air-inlet pipe inclosing a steam-inlet pipe, and an oil-inlet pipe 65 surrounded by a separate steam-inlet pipe, substantially as described.

AUGUSTUS U. PAGE.
JOHN BRAGG.
